UNITED STATES PATENT OFFICE.

JOHN C. HANNETT, OF GRAND RAPIDS, MICHIGAN.

BED-SIDE-RAIL PACKING-BLOCK FOR SHIPMENT OF BED-RAILS.

SPECIFICATION forming part of Letters Patent No. 267,882, dated November 21, 1882.

Application filed April 27, 1882. (No model.)

To all whom it may concern:

Be it known that I, JOHN C. HANNETT, of the city of Grand Rapids, county of Kent, and State of Michigan, have invented a new and 5 useful Improvement in Devices for Packing the Side Rails of Bedsteads, the nature of which will more fully appear from the subjoined description and claim.

Referring to the drawings, Figure 1 represents a perspective view of a block, and Fig. 10 2 a perspective view of the bed side rails having the block attached thereto.

A represents the block, preferably in the form of a parallelopiped, having vertical grooves B 15 and perforations c c, for a purpose that will hereinafter be described.

F represents the side rails of a bed. To each 20 of these rails are attached bed-rail hooks D, the same as those patented December 6, 1870, by the Bradford Joint Company, of Plymouth, Massachusetts. These hooks project from the end of the rail, and are provided with a fang, D', which fits over block A, and a rib, E, which fits into the groove of the block A on the side 25 opposite to the fang D'. The grooves are a sufficient distance from each other to hold the

inner sides of the rails about one-half inch apart. When the block is inserted between the fang and rib of the hooks it is attached to the rails by means of wire, brads, nails, or other device, which is inserted through perforations c c. 30

I am aware that bed-rails have been held together by means of a piece of metal having bent edges, which are driven into the rail. I 35 am also aware that packing-boxes for extension-tables have been provided with grooves for holding the leaves of said table during transportation, and to these I make no claim; but

What I do claim is—

The combination, with bed-rails, provided 40 with hooks having fang D' and rib E, of a holding-block overlapped by fang D' and having grooves B B for ribs E, and holes c c for the 45 securing device, all arranged substantially as described.

JOHN C. HANNETT.
